DISCHARGE-GAP DEVICE

John K. Hodnette and Allan D. Forbes, Sharon,
Pa., assignors to Westinghouse Electric &
Manufacturing Company, East Pittsburgh, Pa.,
a corporation of Pennsylvania

Application January 4, 1936, Serial No. 57,554

5 Claims. (Cl. 175—30)

Our invention relates to the mounting of discharge-gap devices of the type in which a discharge-arc is formed inside of an insulating tube of fibre or other material capable of evolving 5 substantially non-ionized gases in the presence of an arc, with means for discharging the gases to the external atmosphere so as to extinguish the arc.

More particularly, our invention relates to the 10 means for mounting such a discharge-gap device inside of the metal tank of a transformer, or other electrical apparatus, so that porcelain or other substantially non-vaporizable, weather-resistant insulating material is interposed between the discharge-gap device and the tank of the 15 protected apparatus.

Our invention further comprises means for 20 providing an external arc-gap connection, in air, from the internally mounted discharge-gap device just mentioned, to the outside of the tank of the protected apparatus.

A still further feature of our invention is the 25 provision of means for providing an externally mounted series resistor for the internally mounted discharge-gap device previously mentioned, with special gap-means from both terminals of the resistor to the outside of the tank of the protected apparatus.

With the object of providing the apparatus 30 and securing the advantages referred to above, and other objects which will be understood from the description hereinafter, our invention consists in the combinations, structures and systems hereinafter described, and claimed and illustrated in the accompanying drawing, the single figure of which is a longitudinal sectional view through a portion of an electrical apparatus to be protected, and the tank therefor, with a discharge-gap device mounted therein in accordance with our invention.

We have shown our invention as applied to 35 a transformer-tank 1 having one or more high-potential bushings 2 therein, high-potential leads 3, windings 4, a magnetizable core 5, and oil 6 in which the transformer-windings 4 and core 5 are immersed. Mounted within the transformer-tank 1 above the level of the oil 6 is shown one of the protective devices or tubes 7, previously referred to, the same comprising an insulator-tube 8 of fibre, or other arc-responsive volatilizable insulating material, having a closed electrode 9 extending into one end thereof, and a vented electrode 11 extending into the other end thereof, the internal gap-spacing between 50 the electrodes being sufficiently short, as com-

pared to the external flashover-distance around the outside of the insulating tube 8, so that flashover will always occur inside the tube rather than outside thereof. The arcing space between the electrodes 9 and 11 is preferably filled with 5 a multi-slotted diffuser-member 12 made of fibre or other arc-responsive volatilizable insulating material.

In accordance with our invention, the vented electrode 11 is provided with a metallic pipe-like extension 13 extending beyond the insulating tube 8 and extending through a hole or perforation 15 in the wall of the tank 1, above the level of the oil 6 therein. At the place where the pipe-like extension 13 passes through the 15 perforation 15 in the tank, said pipe-like extension is surrounded by a removable flanged sleeve 18 of porcelain or other relatively non-volatilizable, weather-resistant insulating material which fits into said perforation, with the flange 19 of 20 the sleeve 18 against the inside of the tank-wall. A second sleeve 20, also of porcelain or other relatively non-volatilizable, weather-resistant insulating material, surrounds the first sleeve 18 on the other side of the tank-wall, and is 25 clamped thereto by suitable clamping means which are indicated as comprising a gasket 22 and a nut 23.

Inside of the tank, electrical connection is made 30 with the closed electrode 9 by means of a high-voltage jumper 24 which is connected to the high-potential lead 3.

Outside of the tank, an effective surge-discharge connection is made to the end of the 35 metallic pipe-like extension 13 through a resistor 30 which is insulatedly mounted on a bracket 31 by means of a porcelain or other insulator 32. The resistor 30 may comprise a block of molded composition-material 33 which may consist of conducting or semi-conducting 40 particles and a more or less insulating binder. The bottom end of the resistor 30 includes a metal sleeve 34 which is insulatedly mounted on the bracket 31 by means of the insulator 32, 45 the interior of which is partially filled with a plastic insulating compound 35. The outside of the metal sleeve 34 is spaced from the outside of the tank 1 by a gap 36, which is shown as terminating on a metallic bolt 37 attached to 50 the tank. The top end of the resistor 30 is electrically connected to the free end of the pipe-like electrode-extension 13 by means of a metal bracket-member or connector 39 which has a portion 40 which is spaced from the outside wall 55

of the tank 1 by a second gap 41, which is longer than the first-mentioned gap 36.

The resistor 30 is not necessary to be used in every case. When it is used, its function is to limit the magnitude of the power-follow current which follows a lightning-surge discharge in the discharge-gap device 7.

When an excess-voltage surge appears on the high-voltage conductor 3 within the tank 1, the discharge-gap device 1 breaks down internally and flashes over, thus establishing a discharge-current path from the conductor 3 through the jumper 24 to the gap-device 1, and thence through the connector 38 to the resistor 30 and through the short gap 36 to the wall of the tank 1, from which the discharge continues to ground through a suitable surge-discharge path (not shown). When the excess-voltage surge has been discharged, power-current follows through the arc within the discharge gap-device 7 and the arc at the external gap 36, usually until the first current-zero, at which time the deionizing action of the blast in the discharge-gap device is sufficient to extinguish the arc. In case of very excessive current-flow through the resistor 30, the same will eventually flash over, around its external surface. In order to prevent this, the second external gap 41 is provided, which will flash over and form an arc if the ohmic voltage drop in the resistor 30 should become excessive.

It will be observed that our present invention provides means for making certain that the high-voltage lead 3 of the electrical device to be protected is not connected to the tank 1 by any insulating material which is subjected to the repeated plays of electric arcs or which is in any manner affected by weather-conditions or responsive to an electric arc. The fibre, sometimes known as hard fibre, which is preferably utilized as the arc-responsive volatilizable material, has appeared to be perfectly good, in its insulating qualities, even after an extremely large number of very severe discharges of the discharge-gap device; but theoretically, at least, it is subject to a certain small amount of deterioration as a result of exposure to the arc, and it does evolve a certain quantity of semi-conducting carbonaceous particles, together with the substantially non-ionized insulating gases which it evolves. These conducting carbonaceous particles have heretofore all been swept out of the tube by the blast resulting from each discharge, so that they have not been found to accumulate as conducting deposits on the inside walls of the tube. Our invention provides a definite safeguard-means, however, whereby any possible risk in regard to the deterioration of the fibre or the accumulation of conducting deposits is avoided by means of our porcelain-mounting for the discharge-tube.

Furthermore, in previous applications of discharge-tubes to transformer-tanks, where the vented electrode was electrically connected to the tank, and where the series resistor 30 was, of necessity, therefore, mounted inside of the tank between the closed electrode 9 and the high-voltage lead 3, there was a likelihood of an occasional flashover of the resistor, in the space within the transformer-tank above the transformer oil.

We have avoided the possibility of such a discharge by insulating the vented electrode 11 from the tank and by placing the resistor 30 outside of the tank in series electrical connection with the vented electrode 11, so that any resistor-flashover which occurs, as at our second or auxiliary ex-

ternal gap 41, will be outside of the tank, rather than inside the same.

While we have illustrated our invention in a single preferred form of embodiment, it will be obvious that many changes may be made in the design and construction without departing from the essential features of our invention. We desire, therefore, that the appended claims shall be accorded the broadest construction consistent with their language and the prior art. 10

We claim as our invention:

1. A self-extinguishing electrical discharge-device comprising a tube of insulating gas-evolving arc-responsive material, a closed electrode associated with one end of the tube, a high-potential terminal connection for said closed electrode, a vented electrode associated with the other end of the tube, at least one of said electrodes extending into the tube, an electrical ground connection for said vented electrode, said ground connection including a separate open-air series-gap means, and supporting means for said electrical discharge device, said supporting-means including weather-resistant insulating material which is substantially unaffected by an arc, the series-gap means being in shunt relation to said weather-resistant insulating material. 15 20 25

2. An arc-interrupter comprising a tube of insulating material having one end closed and the other end open, electrodes spaced apart internally of said insulating tube and normally insulated from each other, the material of said insulating tube being adapted to volatilize on exposure to an arc to extinguish the arc and expel the gases from the open end of the tube, a metallic pipe-like extension of the electrode at the open end of the tube, said extension extending beyond said tube of insulating material, a removable sleeve of substantially non-volatilizing insulating material surrounding said pipe-like extension, supporting-means surrounding said sleeve, and open-air series-gap means in shunt relation to said substantially non-volatilizing insulating material. 30 35 40

3. In combination with an electrical apparatus 45 having an enclosing metallic tank and a high-potential lead insulatedly passing through said tank, an excess-voltage protective-gap device mounted within said tank and comprising a tubular insulator with an electrode for each end 50 and with gas-evolving insulator-material for evolving gases in a spark-gap space between the electrodes within the tube when subjected to an electric arc, one of said electrodes comprising means for tightly closing its end of the tube, a 55 conductor for electrically joining said electrode to said high-potential lead within the tank, the other electrode being tubular and having a metallic tubular extension extending beyond said tubular insulator, at least one of said electrodes 60 extending into the tube, a flanged sleeve of relatively non-volatilizable insulating material surrounding said tubular extension, said tank having a perforation in a wall thereof for receiving said sleeve with its flange on one side of tank-wall, a second sleeve, also of relatively non-volatilizable insulating material, surrounding the first-mentioned sleeve on the other side of the tank-wall and clamped thereto, and electrical connection-means including an open-air gap-device outside of the tank interposed between said tubular electrode and the tank. 65 70

4. In combination with an electrical apparatus having an enclosing metallic tank and a high-potential lead insulatedly passing through said

tank, an excess-voltage protective-gap device mounted within said tank and comprising a tubular insulator with an electrode for each end and with gas-evolving insulator-material for evolving gases in a spark-gap space between the electrodes within the tube when subjected to an electric arc, one of said electrodes comprising means for tightly closing its end of the tube, a conductor for electrically joining said electrode to said high-potential lead within the tank, the other electrode being tubular and having a metallic tubular extension extending beyond said tubular insulator, at least one of said electrodes extending into the tube, a flanged sleeve of relatively non-volatilizable insulating material surrounding said tubular extension, said tank having a perforation in a wall thereof for receiving said sleeve with its flange on one side of tank-wall, a second sleeve, also of relatively non-volatilizable insulating material, surrounding the first-mentioned sleeve on the other side of the tank-wall and clamped thereto, a resistor element outside of the tank, and electrical connecting and mounting means for said resistor whereby one

terminal of the resistor is connected to said tubular extension and electrically separated from the tank by an open-air gap of predetermined length, while the other terminal of the resistor is electrically separated from the tank by a shorter 5 open-air gap.

5. The combination, with an excess-voltage protective element of a type capable of interrupting the arc following an excess-voltage discharge, of a conducting supporting-member, means for insulatingly mounting one terminal of said protective element on said conducting supporting-member, a resistor-element electrically connected, at one end, to said terminal of said protective element, and insulating mounting-means 10 for said resistor-element whereby the end of the resistor-element which is connected to the protective element is electrically separated from said supporting-member by an open-air gap of predetermined length, while the other end of the 15 resistor-element is electrically separated from said supporting-member by a shorter open-air gap.
